UNITED STATES PATENT OFFICE

144,202

DESIGN FOR A LECTERN CABINET

Joseph M. Loge, Los Angeles, Calif.

Application August 6, 1945, Serial No. 121,251

Term of patent 14 years

(Cl. D26—14)

To all whom it may concern:

Be it known that I, Joseph M. Loge, a citizen of the United States of America, residing in the city of Los Angeles, in the county of Los Angeles, State of California, have invented a new, original, and ornamental Design for a Lectern Cabinet, of which the following is a specification, reference being had to the accompanying drawings, forming a part thereof.

Fig. 1 is a front perspective of a lectern cab-

inet showing my new design in closed position.

Fig. 2 is a rear elevational perspective view of the cabinet in closed position, and

Fig. 3 is an exploded perspective view of the cabinet in open position ready for use.

I claim:

The ornamental design for a lectern cabinet, substantially as shown and described.

JOSEPH M. LOGE.
